Atty's.

UNITED STATES PATENT OFFICE.

WILLIAM G. SHELTON, OF ST. LOUIS, MISSOURI.

STEAMING-TUBE PLUG.

Application filed December 19, 1927. Serial No. 241,107.

My invention relates to equipment utilized in hair waving and consists in a novel device for sealing the end of a steaming tube next to the scalp of the person whose hair is being waved.

In one process of waving the hair, it is customary to use a steaming tube formed of foil and surrounding a strand of hair wrapped around a curling rod, there being a moisture containing element of absorbent material either wrapped about the hair independently of the tube or included in the tube structure within the layer or foil. When the absorbent material is applied to the hair, it is moistened and, when the tube is heated, steam is created. It is desirable to prevent the escape of the steam from the tube and particularly to prevent the escape of the steam, or hot water formed by the condensing of the steam, through the end of the tube which is adjacent to the scalp of the person whose hair is being waved. One way of closing the end of the tube has been to crimp the sides together, either with the fingers or by use of a plier-like crimper.

Such closure of the end of the tube is not always certain and, if a passage is left for the escape of steam or condensation, the user may be scalded. The tube must be crimped at a point spaced from its end, hence the strand of hair cannot always be crimped as near to the scalp as may be desired. Since flannel or blotting paper, usually utilized for the absorbent material, does not retain its form when crimped, it is customary to terminate the latter at some distance from the end of the foil and, as this leaves the foil free to contact directly with the hair, there is created the possibility of burning the hair in the event of the foil becoming a conductor of the electric current supplied to the heater.

The object of my invention is to eliminate the above-mentioned disadvantages and to provide a simple and efficient plug for the purpose indicated.

In the accompanying drawings which illustrate a selected embodiment of my invention—

Figure 1 is an illustration of a steaming tube applied to a strand of hair with my improved plug assembled therewith.

Figure 2 is an elevational view of the plug.

Figure 3 is a vertical longitudinal section through the same.

Figure 4 is a top view of the same.

The plug itself consists of a cup-like element preferably formed of vulcanized rubber fibre, bakelite, or other rigid and preferably insulating material. The bottom 1 of the plug is flat and of substantial thickness, and the sides 2 which extend upwardly from the bottom and near the upper open end of the plug are conical in shape, as indicated at 3, to more readily permit insertion of the plug into the open end of a steaming tube 4 and to slightly spread the end of the tube so as to form a tight joint between the same and the plug.

The steaming tube 4 is shown as consisting of several layers of foil and absorbent material, such as blotting paper or flannel, and for the purpose of clearly illustrating the use of my invention, the thicknesses of these layers are magnified in the sectioned portion of Figure 1.

The side of the plug is provided with a longitudinal slot 5 extending from the open end of the plug to the inner bottom thereof and the bottom of the plug is provided with a notch 6 in line with slot 5. The slot 5 and notch 6 provide a passage-way for the portion 7 of a strand of hair between the scalp 8 and a curling rod 10 about which the hair is wound.

Preferably the sides of slot 5 converge near the lower end of the slot and notch 6 is so shallow that a portion of the strand of hair will project beyond the side of the plug thereby eliminating the likelihood of any open passage-way between the hairs of the strand or between the strand and the side of the steaming tube.

I have illustrated the use of a felt washer 8 and a fibre clip 9 about the strand of hair below the steaming tube. These elements are in general use and form no part of my present invention. They have been relied upon heretofore to protect the scalp from fluids leaking from the tube. The closing of the tube has been attempted by crimping the lower end similarly to the crimping of the upper end illustrated. My plug closure of the lower end of the tube bar more effectively seals the latter than the crimping operation.

It will be noted that the inner bottom of

the plug is concave and this provides a recess for seating the lower end of the curling rod 10. If the steaming tube stands upright, as shown in Figure 1, this concavity will 5 serve as a receptacle for condensate moisture. This feature and the other elements of my invention permit the hair to be steamed closer to the scalp than is feasible with the steaming tubes previously used and, at the 10 same time, the comfort and safety of the user is not menaced.

I contemplate the exclusive use of my invention not only in the preferred form illustrated, but in such modified forms as come 15 within the scope of my claims.

I claim:

1. As a new article of manufacture, a closure for a hair waving steaming tube comprising a cup-shaped plug with a longitudinally disposed slot in its side adapted to receive a strand of hair.
2. As a new article of manufacture, a closure for a hair waving steaming tube comprising a cup-shaped plug, the side wall 25 of which is conically shaped near the upper end to facilitate insertion into the end of a steaming tube to spread and seal the same, there being an opening in said side wall adapted to receive a strand of hair.
3. As a new article of manufacture, a closure for a hair waving steaming tube comprising a cup-shaped plug, the side wall 35 of which is conically shaped near the upper end to facilitate insertion into the end of a steaming tube to spread and seal the same, there being an opening in said side wall near the bottom of the cup adapted to permit the passage therethrough of a strand of hair.
4. As a new article of manufacture, a closure for a hair waving steaming tube comprising a cup-shaped plug, the side wall 40 of which is conically shaped near the upper end to facilitate insertion into the end of

the steaming tube and to more readily form 45 a tight joint between the plug and the tube, said side wall being provided with a slot extending from the open end of the cup to a point near the bottom of the cup and converging near said point, the edge of said bottom having a notch in line with said slot, said slot and notch being adapted to receive a strand of hair.

5. As a new article of manufacture, a closure for a hair waving steaming tube 55 comprising a cup-shaped plug of rigid material having a cylindrical side wall adjacent its bottom and a conical side wall adjacent its open end, said cup being adapted to receive the lower end of a curling 60 rod and a strand of hair wound around the same, and said side wall being provided with a slot extending longitudinally of the cup and adapted to receive and compress the strand of hair between the curling rod and 65 the scalp.

6. In combination, a hair waving steaming tube and a plug inserted in the end of said tube which goes next to the scalp, said plug being tapered to tightly fit the tube 70 and provided with an opening adjacent to the end of said tube for receiving a strand of hair being waved.

7. In combination, a hair waving steaming tube formed of multiple layers of absorbent material, and a plug inserted into the end of said tube which goes next to the scalp, said plug being tapered to enter the tube and compress the material of the latter 75 to form a tight joint therewith, said plug being provided with an opening adjacent to its lower end for permitting the passage 80 therethrough of a strand of hair being waved.

In testimony whereof I hereunto affix my 85 signature this 15th day of November, 1927.

WILLIAM G. SHELTON.
